UNITED STATES PATENT OFFICE.

GODFREY HENRY HARRIS, OF NEW YORK, N. Y.

DESIGN FOR A POKER CHIP OR THE LIKE.

61,340.

Specification for Design.

Patented Aug. 8, 1922.

Application filed February 17, 1922. Serial No. 757. Term of patent 7 years.

To all whom it may concern:

Be it known that I, GODFREY HENRY HARRIS, a citizen of the United States, and a resident of the borough of Manhattan, in the city and State of New York, have invented a new, original, and ornamental Design for Poker Chips or the like, of which the following is a specification, reference being had to the accompanying drawings, forming part hereof.

In the said drawings, Fig. 1 is a plan view of a poker chip, embodying my new design, and Fig. 2 is an edge view of the same.

I claim:

The ornamental design for a poker chip or the like, as shown.

In witness whereof I have hereunto signed my name at the city of New York, State of New York, this 15th day of February, 1922.

GODFREY HENRY HARRIS.
